M. J. LOWRY

TOY BASEBALL GAME

Filed Nov. 23, 1926

Attorney

UNITED STATES PATENT OFFICE.

MICHAEL J. LOWRY, OF LOS ANGELES, CALIFORNIA.

TOY BASEBALL GAME.

Application filed November 23, 1926. Serial No. 150,238.

The present invention relates to game apparatus and has for its principal object the provision of an improved apparatus for simulating the game of base ball and which is 5 more particularly adapted for use as an indoor or house game.

The invention contemplates the provision of a mechanical pitcher capable of convenient manual manipulation for delivering the ball in the direction of a batter and to provide a mechanical batter for manual manipulation to bat the ball delivered by the pitcher.

Likewise, there is a device for intercepting the ball delivered by the pitcher when the 15 batter fails to strike the ball, whereby a strike indicia is automatically exhibited.

In the drawings:—

Fig. 1 is a perspective view of a game apparatus embodying the novel features of the 20 present invention;

Fig. 2 is a section on line 2—2 of Fig. 1, illustrating the connection means for the sections of the board;

Fig. 3 is a section on line 3—3 of Fig. 1, illustrating the supporting means for a ball intercepting device;

Fig. 4 is an enlarged detail view of the pitcher and pitching apparatus;

Figs. 5 and 6 are side and rear detail views 30 of the same;

Figs. 7, 8 and 9 are detail, front, side and rear views of the batter illustrating the batting apparatus;

Fig. 10 is a vertical section of the ball intercepting device;

Fig. 11 is an elevation of the same with the strike indicium displayed;

Fig. 12 is a perspective view of a baseman, illustrating the supporting medium of the 40 same.

Like characters of reference indicate corresponding parts in each of the several figures of the drawings.

The apparatus includes a playing field or 45 board, which is preferably formed in two sections 12 and 13, connected together by the upper and lower plates 14 and 15, as clearly illustrated in Fig. 2.

The board may be covered with some suitable material, such as billiard cloth, and a miniature diamond is marked off on the cloth with the bases defined as in the ordinary ball field.

Mounted on the board adjacent the home 50 plate, rearward of the home plate and at the

pitcher's box, are keepers designated at *a*, *b*, and *c*, respectively, each of which embodies a metallic strip the end portions of which are secured to the board by rivets, or other suitable fastenings, and the intermediate portions *d* of which extend parallel with the board in spaced relation thereto to form slots *e*, as shown in Fig. 3.

At the rear of the home plate there is located a ball intercepting device suitably illuminated, as illustrated in Fig. 11 and the same comprises a rectangular sheet of material 16, on which is printed or otherwise illustrated, the simulation of a player in the crouched position for catching a pitched ball. 70 This device while depicting a catcher functions as an umpire to indicate "balls" and "strikes" according to the manner in which a ball is delivered relatively to the home plate.

The metal at central part of the plate 16 is 75 stamped out to provide transverse opening and resultant of the stamping operation to provide the opening, an oblong piece of metal 17 is formed and the said metallic piece is connected to the metal sheet 16 by a hinge 18 80 and provides a closure for the said opening adapted to open rearwardly of the metal sheet. The lower end of the plate 16 is formed with a tongue 18' which is insertable under the keeper *b* to fixedly yet removably 85 attach the plate 16 to the board.

A pitcher 19 is stamped out of sheet metal and has its lower end connected to the horizontal extension 20 of an angle plate 21, the vertical extension 22 of which has connected thereto a stud 23, on which is rotatably 90 mounted an arm 24, adapted to be normally held in upright position by means of a spring element 25, the major portion of which is coiled around the stud 23. The lower end 95 of the spring 25 is connected to a lip 26 upstruck from the horizontal part 20 of the angle plate 21, while the upper end is bent over to form a hook 27, which engages over the inner longitudinal edge of the arm 24.

The upper end of arm 24 has secured thereto in any appropriate manner, a wire pocket 28 and a cord 29 is connected to the arm adjacent its upper end. By placing a ball, such as an ordinary marble in the pocket 28 and pulling rearwardly on the cord 29, the spring 25 is tensioned on the stud, and upon release of the cord, the pitching arm 24 will be manipulated to deliver the ball to the batter.

The plate 21 is formed with a tongue 21' insertable under the keeper *c* to fixedly yet removably attach the pitcher to the board and whereby the body portion of the pitcher is held stationary.

The batter 30 is supported in upright position by an angle plate 31 of identically the same construction as the supporting plate 21 for the pitcher and a similar stud 32 projects outwardly from the vertical extension of the plate and has coiled thereon a spring 33, the lower end of which is connected to a lip 34 on the longitudinal extension of the plate. An arm 35 is mounted on the stud 32 and the upper part of the plate 33 is connected thereto. Secured to the upper horizontal extension 36 of the arm 35 is a tubular element 37 adapted for the reception of the handle end of a bat 38. A cord 39 is attached to the upper part of the arm 35 and when the same is pulled, the arm 35, carrying bat 38 is moved rearwardly and when released, the spring 33 functions to return it to its normal position.

By means of the cord 39 the bat 38 is oscillated or swung to get a line on the ball delivered from the pitcher and the operator upon getting the proper focus on the ball, releases the cord and the bat is swung in an endeavor to hit the ball in imitation of the batting movement employed in the ordinary game of base ball.

The oscillating arms 24 and 35 carrying the ball and bat are yieldably maintained in their normal position as before stated, by the springs 25 and 33 and the oscillating movement in both directions is limited by means of the stationary stop projections 40 and 41 formed on the upper curved edge of angle plates 21 and 31.

The plate 31 is formed with a tongue 31' engageable with the keeper *a* to hold the body portion of the batter stationary.

The basemen 42 are duplicates and a description of one will suffice. Each baseman is stamped out of sheet metal and is formed with a base supporting flange 43 by means of which it is supported in position at the proper base.

In the operation of the invention, the pitcher, batter and the ball intercepting device are stationarily affixed to the board by engaging the tongues on their respective body portions with their related keepers; the tongues and keepers thus affording a means whereby these members will be securely held against movement relatively to the board. The basemen pieces are loosely set in place on the board in their respective positions; being unattached to the board so that they may topple over in event they should be struck with the ball with such force or in such manner as to upset them during course of the play. One player of the game takes a position to manipulate the cord for actuating the pitcher and the other player is positioned to manip-

ulate the cord for actuating the batter. In playing the game, a ball is placed in the pocket 28 and is projected toward the batter by retracting the arm 24 in opposition to the spring 25 by pulling on the cord 29 and then suddenly releasing the cord so as to cause the spring 25 to advance the arm and thereby impel the ball on the arm impacting against the stop 40. The batting player then endeavors to cause the bat 38 to strike the ball, which is effected by retracting the arm 35 in opposition to the spring 33 by pulling on the cord 39 and suddenly releasing it, as before described. If the ball is thus struck, it may be considered either a fair ball or a foul according to the usual rules of a base ball game. If a fair ball is struck it will entitle the batting player to a score, unless it should knock over a baseman in which event it would be considered an out. In event the bat missed the ball a strike would be counted if the ball entered the opening in the ball intercepting device, but should the ball miss the opening the play would be counted as a ball. In order to insure the possibility of the bat striking the ball, and also insure the ball being occasionally directed through the opening in the ball intercepting device, the opening in the latter and the bat are positioned on the normal line of travel of the ball, and the ball impelling arm 24 with the pocket 28 are arranged in such relation to the bat and opening that under the urge of the spring, properly tensioned, the ball will ordinarily traverse a line of travel leading to the opening in the ball intercepting device and in which the bat is interposed.

Although I have herein illustrated and described only one form of apparatus embodying my invention, it is to be understood that various changes and modifications may be made thereto without departing from the spirit and scope of the appended claims.

What I claim is:—

1. In a game apparatus, a board, a pitcher embodying a plate formed to represent a miniature base ball player, a keeper on said board, a tongue on said plate engageable with said keeper to detachably secure said plate stationary on said board, a vertically swinging arm pivoted on said plate, a ball receiving pocket mounted on the arm, spring means for actuating the arm to throw the ball from the said pocket, a cord attached to said arm adapted to be manually pulled to retract said arm in opposition to said spring, and a stop on said plate for limiting forward movement of said arm.

2. In a base ball game apparatus, a board basemen each having a supporting flange to seat loosely on said board, a mechanical pitcher having a vertically swinging arm and a ball-receiving pocket connected thereto, a spring on said pitcher operable to advance said arm, a cord connecting with said arm

operable to effect retraction of the arm in opposition to the spring, a mechanical batter, having an oscillating bat, a spring carried by said batter for advancing said bat, a cord 5 operable to retract the bat in opposition to the spring, means for intercepting the ball arranged adjacent the batter, a series of keep-

ers on said board and means on the pitcher, batter and ball intercepting means detachably and stationarily engageable with said keepers in their respective positions. 10

In testimony whereof I have affixed my signature.

MICHAEL J. LOWRY.
